UNITED STATES PATENT OFFICE.

JOHN ELLIS, OF WEST VIEW, PENNSYLVANIA.

WATER HEATER.

Application filed March 11, 1926. Serial No. 93,837.

My invention relates to improvements in water heaters, relating in particular to the so-called instantaneous automatic water heaters employing gas as the heating medium and having water motor and thermostatic control.

One object of my invention is to provide an operating mechanism for the above class of heaters that will permit a given supply of hot water, of full or partial volume, as desired, being delivered at the faucet, whether it be located at the level of the heater or at an elevation thereabove, such as at the second or third floor of a dwelling.

Another object of my invention is to supply the water at such elevations at a substantially like temperature whether the faucet be fully opened or not and in accordance to the temperature limit to which the thermostat be set.

Further objects of my invention are, to provide control mechanism that will be simple in construction, of few parts, and that is not liable to become inoperative.

With the above objects in view, the invention consists in certain novel features of construction, in certain parts and combinations as will be hereinafter more fully described and particularly pointed out in the appended claims.

In the accompanying drawings, forming a part of this specification, I have illustrated one embodiment of my invention, wherein

Figure 1 is a side elevation of a heater having my improved operating mechanism applied thereto.

Fig. 2 is a front elevation of a part of the mechanism taken on line II—II of Fig. 1.

Fig. 3 is an enlarged side elevation of the valve mechanism.

Fig. 4 is an end elevation of the secondary water-controlling valve, and

Fig. 5 is a longitudinal sectional view of said valve.

Referring to the drawings for a detailed description of the heater and the operation thereof, the numeral 1 designates the heater shell, it being assumed that the same contains a heating coil, gas burner and pilot light, not shown, of conventional type. A suitable gas valve 2, is also included in the gas line 3.

The hot water service line 4 leading to the various supply faucets and the upper end of a tubular thermostat 5 are threadably secured to the upper end of an open valve

supporting frame 7, fixed to the heater, and rigidly held by nuts 6. The lower end of the thermostat is connected to the lower portion of the heater coil (not shown), by a connector 8 and is adjustably held within the frame by a bridge piece 9. The frame carries at its lower end a loosely fitted thrust pin 10 which engages the thermostat connection 8, said frame being provided with spaced downwardly-extended flanges 11 and 12, respectively, each having an oppositely disposed groove 13 therein. The flange 12 extends down beyond the other, but each are provided with a lug 14 and 15, respectively, one disposed opposite the other, said lug 14 supporting the water motor 16 and the lug 15 supporting the gas valve 2. A thermostat lever 18, terminating at its lower end in a fork 19, is suspended between the flanges of the frame by the knife-edged projections 20 thereon engaging in the flange grooves 13. The lever is provided, near its point of suspension, with a shouldered portion 21 carrying a set screw 22, engaging the thrust pin 10, said screw being adapted to adjust the lever to the desired temperature-operating position with respect to the thermostat.

The motor, or gas and water control device 16, comprises a chamber casing 23 provided with an intake water extension 24 connected to the cold water inlet line 25 and an outlet extension 26 to the pipe 27 that connects the upper end of the heater coil (not shown). Within this casing is formed the main or water motor chamber 28, closed at its rear end by a removable head 29 and communicating at that end with the cold water inlet 24 by a port 30, and also communicating with the cold water outlet 26. The water inlet 24 also communicates with the main water chamber by the port 31, valve opening 32, inlet chamber 33, formed in extension 34, and the port 35, there being also provided a small chamber 36 opening 100 into the port 31. Within the water motor chamber 28 is operatively fitted a piston 37 having a stem 38 extending through a stuffing box 39 and cap 40, said stem being in line with the stem 41 of the gas valve 2. The piston is normally held in engagement with the extension 42 of the head 29 by a helical spring 43, said piston being provided with a normally-closed primary piston valve 44, held in position by a spring 45 and provided with a suitable small port or other water passage 46. Passage of cold water

from the main or inlet 24 to the chamber 28, by way of valve port 31, valve opening 32, chamber 33 and port 35, is controlled by a secondary valve member 47. The valve is provided with a stem 48 having a head 49 thereon, the stem extending through the stuffing box caps 50 and 50' and is surrounded by a spring 51 to normally hold and return the valve to its seat. The head of the valve stem is engaged by the forked end of the thermostat lever by which means the valve is opened. The cylindrical valve member 47 extends at its rear, through an opening into the chamber 36 and has its forward end, or valve proper 52, enlarged and provided with a tapered face to engage the correspondingly tapered seat about the opening 32. The valve member is reduced in diameter between its ends, the shoulders formed thereby being of equal diameter and area. Ports 53 are formed through an extension at the stem end of the valve and opening into the interior thereof, providing communication between the chambers 33 and 36 to permit water therethrough, whereby the valve may move freely.

Operation.

When a faucet in the hot water line 4 is opened, the water pressure on the right side of the piston 37 is reduced, causing the pressure of the incoming cold water on the left side to predominate and move the piston to the right against the tension of the spring 43. As the piston moves, the stem 38 engages the stem of the gas valve and opens the valve to turn on the gas at the burner (not shown), it being assumed that the heater contains the usual pilot light for igniting the gas at the burner. The forward movement of the piston also causes the primary piston valve 44 to come into engagement with the forward end of the chamber, as shown by dotted lines, compressing the spring 45 thereof and permitting a small stream of water (much less the capacity of the heater) to pass through the small port 46 thereof to the heater coil.

The moment the heated water begins to move through the thermostat 5 it gradually expands and actuates the lever 18 which in turn moves the secondary valve 47 controlling the main water supply from its seat and permits a supply of water to pass from the cold water intake 24 to the right side of the chamber 28 and into the heater coil. As the temperature of the water in the coil increases the thermostat continues to operate and further open the valve 47 thus increasing the supply of water to the coil until the proper temperature at which the thermostat is set for controlling the incoming cold water is reached, the valve 47 then remaining open for the passage of a fixed quantity of cold water to the heater and consequently

a like quantity of hot water at the faucet, of fixed temperature.

When the faucet is closed, the pressure of the water, plus that of the piston spring, returns the piston to normal position, thus allowing the gas valve to close and cut off the heat at the burners. At this time the cold water control valve 47 returns to its seat by the cooling of the thermostat. The secondary valve being provided with a shouldered portion, between its piston and valve ends, the pressure of the water within the incoming port 31 against said shoulders will be equalized, thus providing a practically balanced valve structure.

When water is drawn from a faucet, either at the heater level or an elevation thereabove, thus reducing the pressure of the water in the line from the heater, it causes the water in the heater to become momentarily increased in temperature. During such operation, the thermostat mechanism automatically adjusts itself to move the secondary inlet valve, permitting more cold water to be supplied to the heater, and thus providing water supply of predetermined temperature and desired capacity at the faucet.

When a faucet in the hot water supply is but partly opened, the same action as above occurs for full or practically full capacity, except that the piston will automatically adjust itself back and forth in order to control the gas to the burner. However, the thermostat mechanism will move only to and remain stationary at a point where the temperature is reached, regardless of the quantity delivered at the faucet.

During operation, the primary valve being open, the small supply of incoming cold water to the heater coils prevents said coils overheating until the water enters the thermostat to operate the secondary valve.

Having shown and described one embodiment of my invention, what I claim is:

1. In a water heater, the combination of a water motor comprising a water cylinder having a movable piston slidably fitted therein, a primary water inlet valve carried by the piston, a gas valve operated by said motor piston, a thermostat lever, a thermostat, and a main water inlet valve independent of the piston, the primary water valve adapted to admit a small quantity of water to the heater when the gas valve is operated by the motor piston and the main water valve adapted to open to increase the quantity of water to the heater by movement of the thermostat and actuated lever.

2. In a water heater, the combination of a water motor comprising a water cylinder having a movable piston slidably fitted therein, a primary water inlet valve carried by the piston, a gas valve operated by said motor piston, a thermostat lever, a thermo-

stat, and a main water inlet valve independent of the piston and having a ported sleeve body portion disposed in the direct water passage to the heater, the primary water valve adapted to admit a small quantity of water to the heater when the gas valve is operated by the motor piston and the main water valve adapted to open to increase the quantity of water to the heater by movement 10 of the thermostat and actuated lever.

3. In a water heater, the combination of a water motor comprising a water cylinder having a movable piston slidably fitted therein, a primary water inlet valve carried 15 by the piston, a gas valve operated by said motor piston, a thermostat lever, a thermo-

stat, and a main water inlet valve independent of the piston and having a sleeve body portion provided with both inlet and outlet ports and disposed in the direct water passage to the heater, the primary water valve adapted to admit a small quantity of water to the heater when the gas valve is operated by the motor piston and the main water valve adapted to open to increase the quantity of water to the heater by movement of 20 the thermostat and actuated lever.

In testimony whereof, I have hereunto subscribed my name this 5 day of March, 1926.

JOHN ELLIS.
